BUSHING CAP

Alexander A. Skvortzoff, Sharon, Pa., assignor
to Westinghouse Electric & Manufacturing
Company, East Pittsburgh, Pa., a corporation
of Pennsylvania

Application February 18, 1941, Serial No. 379,461

4 Claims. (Cl. 174—167)

The present invention relates to bushings for insulating the high potential leads to electrical apparatus such as transformers and circuit breakers, and it has particular relation to an improved cap for sealing the exposed ends of such bushings.

Apparatus of the type contemplated generally includes a tubular casing of dielectric material such as porcelain through which extends a conducting member which may be in the form of a metallic stud or tube. In such apparatus the lower end of the casing is generally fixed relative to the stud and a metallic cap member is disposed at the upper end to close the interior of the bushing against the entrance of outside atmosphere and impurities which may be carried thereby.

Due to differences in the expansion properties of the casing and stud in response to temperature changes, it is necessary to provide a cap structure such that no dangerous stresses will be imposed upon the casing during contraction of the stud and all of the sealed joints will be maintained closed during the expansion thereof.

According to the present invention, a metallic cap which is provided to close the bushing is rigidly secured to the stud at its top and has an open bottom. A flexible diaphragm is secured to the bottom of this cap and arranged to completely seal the space between the cap and the casing irrespective of any relative movement which may occur as a result of temperature changes.

It is, accordingly, an object of the present invention to provide a novel and improved high potential insulating bushing.

It is another object of the invention to provide an insulating bushing with a cap structure which is inexpensive to manufacture, easy to assemble and dismantle, and particularly satisfactory in operation.

Still another object of the invention is to provide an insulating bushing cap which may be rigidly supported from the bushing stud and yet includes a flexible metallic diaphragm for closing the insulating casing irrespective of any relative movement between the parts.

A further object of the invention is to provide a bushing of the above type which may be tested without the necessity of disconnecting an inside terminal of the conductor from the electrical apparatus with which the bushing is being employed.

Other objects and advantages of the invention will appear from the following detailed descrip-

tion read in conjunction with the accompanying drawing, in which:

Figure 1 is a vertical sectional view of an insulating bushing embodying the present invention;

Fig. 2 is a reduced scale horizontal sectional view of a portion of this apparatus taken along the line II—II of Fig. 1; and

Fig. 3 is a portion of a similar view of a modification of the invention.

Referring to Fig. 1, the apparatus includes a tubular casing 2 which may be of porcelain or some other suitable insulating material, and which is equipped with the usual surface creepage flanges indicated at 4. A metallic stud 6 extends axially through this casing and projects beyond its end as indicated in the drawing. The stud 6 may be solid as shown or in the form of a copper tube, in each of which cases it may serve as the lead conductor. It will also appear that the stud need not necessarily serve as the conductor, but may include a fished through lead of a usual type for this purpose.

A condenser member 8 which may be built up of alternate layers of conductor and dielectric material in a manner well known in the art is preferably disposed about the stud 6 within the casing. It will be understood that a usual type of metallic connecting flange is intended to be fixed to this condenser member at substantially its mid-point and the lower end of the casing 2 arranged to rest thereon to thus relatively fix these portions of the apparatus. Since this part of the structure is well known in the art, it is not completely illustrated. A more complete showing of such a structure will be found in my copending application, Serial No. 235,611, filed October 18, 1938, and granted as Patent No. 2,228,089.

The upper portion of the exposed end of the stud 6 is screw-threaded as indicated at 10 to aid in supporting a terminal cap designated as 12. This terminal cap includes a top portion 14 threaded onto the stud and preferably sweated or soldered thereto at 11. A side wall portion 16 of the cap is secured to the portion 14 by bolts 18 and is suitably gasketed at 20 to provide an airtight seal. The bottom of this side wall portion 16 is open as at 22 and this opening is defined by a vertical cylindrical surface 24.

A base plate 26 is provided with an annular groove 28 which is adapted to receive a pair of gaskets 30 and 32. These two gaskets may be of the well known construction such that the inner gasket 30 is relatively resilient to supply a seal-

ing action while the outer gasket 32 acts in the nature of a stop therefor. As is most clearly shown in Fig. 2, this base plate 26 is provided with a central aperture through which the stud 6 extends and includes inwardly extending spacing fingers 27 for slidably engaging the stud to center itself thereon. The base plate is seated on the upper end surface 34 of the insulating casing 2 with the gaskets 30 and 32 disposed therebetween to form an air-tight seal in the manner described above.

A flexible metallic diaphragm 36 is secured to the upper portion of the surface 24 of the cap as by brazing at 38 and includes a central aperture which is considerably larger than the diameter of the stud 6 to prevent its making contact therewith. The inner edge of this diaphragm is arranged to rest on a raised inner perimetral portion 40 of the base plate, which portion is preferably grooved as shown to carry a sealing gasket 41. It will appear that the outside dimensions of this base plate are such that its outer edge surface makes a sliding fit with the surface 24 of the cap so that it is movable within the opening therein.

An annular clamping plate 42 includes a downwardly projecting seat portion 44 arranged to contact the upper surface of that portion of the flexible diaphragm which engages the portion 40 of the base plate. This clamping plate is preferably provided with spacing fingers around its opening similar to those indicated at 27 on the base plate to center it about the stud in slidable relation thereto. A number of spaced depressions or seats 46 are formed in the upper surface of this clamping plate to be engaged by bolts 48 forming part of a biasing or clamping assembly.

This clamping assembly includes a fitting 50 which is threaded to the portion 10 of the stud 6 and is preferably in the form of a spider having a hole 52 in each of its fingers. In the apparatus shown, four such fingers are provided and one of the bolts 48 is loosely disposed in each of them. An annular plate 54 is provided with bosses 56 spaced similarly to the holes 52 and having screw-threaded apertures therein. One of the bolts 48 extends through each of these apertures and a helical spring 58 surrounds each bolt so as to be compressed between the fitting 50 and plate 54.

It will thus be seen that the bolts 48 exert a downward pressure on the clamping plate 42 which, in turn, presses downwardly on the flexible diaphragm 36 to seal the joint between this diaphragm and the base plate 26. This same pressure also acts to bias the plate 26 downwardly relative to the stud 6 to exert a sealing pressure on the gaskets 30 and 32. Thus, with the main portion of the cap rigidly secured to the stud, the base plate 26 is free to slide longitudinally therein as a result of temperature changes. At the same time the diaphragm keeps the interior of the cap sealed despite any such movement.

The method of assembling the above described device will be found particularly convenient. After the insulating casing 2 is disposed around the stud 6, the base plate 26 is centered on the stud and brought to rest upon the end of the casing. The side wall portion 16 of the cap is then placed on the assembly with the flexible diaphragm 36 in its proper position relative to the base plate, after which the interior portions of the cap may be assembled in a manner which will appear evident. The bolts 48 are then ad-

justed to compress the springs 58 the desired amount. After this is done, the top 14 of the cap may be threaded into position, bolted to the portion 16 and soldered or brazed to the stud. It will be evident that the entire assembly may be completed without using any press or special tools.

In order to further simplify this assembly operation, it is preferred to provide a number of screw-tapped holes 57 around the periphery of the base plate and to secure washers 59 thereto by means of machine screws 60. With the washers 59 extending past the surface 24 of the cap portion 16, it will appear that the base plate will act to prevent the portion 16 from moving downwardly during the assembly operation. After the device is assembled the washer 59 and screw 60 must, of course, be removed.

While the construction described above provides a particularly satisfactory cap for an insulating bushing, it will, nevertheless, appear that the power factor testing of such a bushing cannot be accomplished without disconnecting the line from the upper end of the stud 6 and also disconnecting the electrical apparatus being supplied from the lower end thereof. In the modification of the invention shown in Fig. 3 I have provided an arrangement which greatly simplifies the testing operation.

Referring to Fig. 3, a thin layer 62 of insulating material is disposed on the surface of the stud 6' along the greater portion of its length and extends up past the clamping plate 42'. A coating 64 of conducting material is then applied to the surface of this insulating material within the insulating casing 2'. A condenser member 8' which is otherwise similar to that of Fig. 1 is then applied to the stud over these two coatings.

In this modification, the base plate 26', instead of being completely metal, is provided with a ring 66 of insulating material such as micarta at its outer edge or perimeter. The ring 66 thus slidably engages the surface 24' of the hole in the cap portion 16' to permit the base plate assembly to move relative to the cap. In addition, the raised portion 40' of this base plate is not grooved as in the previous case but a gasket member 41', is disposed thereon between a pair of non-compressible insulating gaskets 68 which may, for example, be of asbestos material. The flexible diaphragm 36' is thus completely insulated from the base plate and the stud.

A conducting member 10 is electrically connected to the conducting coating 64 as by soldering at 72, and serves to electrically connect it to the base plate 26' by means of a screw 74. Another flexible conductor 76 is secured to the base plate 26' at 78 and is removably attached to the cap portion 16' at 80. It will appear that this conductor 76 will electrically connect the cap to the conductor member during normal operation of the bushing. During power factor testing, however, the conductor 76 may be disconnected at 80 and the base plate 26' connected to the testing apparatus, the other end of which may be secured to the metallic clamping flange. During such testing operation, the cap, stud and consequently the apparatus within the tank are completely disconnected and the power factor of the bushing from the conducting covering 64 may be readily ascertained. If the shielding circuit of the test set is connected directly to the body of the cap, the difference in potential between the stud 6' and the bottom plate 26' will be so small

that the insulation provided by the ring 66 and gaskets 68 will be ample to withstand it.

From the above description, it will appear that the present invention provides an insulating bushing with a cap structure which is inexpensive to manufacture, simple to install, and which will provide most satisfactory operating properties. In addition, the apparatus may be easily dismantled for repairs in the field and readily adapted for convenient power factor testing.

Since various modifications of the apparatus shown and described in detail will appear to those skilled in the art, it is intended that the invention will be limited only by the appended claims interpreted in view of the prior art.

I claim as my invention:

1. In a bushing for high tension electrical apparatus including a tubular casing of insulating material having a stud extending axially therethrough and projecting beyond an end thereof, said stud having a portion thereof fixed with respect to a portion of said casing; a cap extending around and secured to the projecting portion of said stud and having an open bottom portion, a base plate proportioned to seat on the adjacent end face of said casing and fitting in movable relationship into said cap to substantially close the open bottom thereof throughout a predetermined range of movement therebetween, a flexible member disposed within said cap for sealing the space between it and said base plate, and means for biasing said base plate against said tubular casing.

2. In a bushing for high tension electrical apparatus including a tubular casing of insulating material having a stud extending axially therethrough and projecting beyond an end thereof, said stud having a portion thereof fixed with respect to said casing; a cap extending about the projecting portion of said stud and having an opening defined in its bottom by a substantially vertical surface portion, means for securing said cap to the projecting portion of said stud, a base plate positioned to seat on the adjacent end face of said casing and extending into said bottom opening in the cap, said base plate being of a shape similar to and slightly smaller than said opening and being movable therein to substantially close said cap despite relative movement within predetermined limits therebetween, a flexible diaphragm sealed to said cap adjacent the edge of said opening and having its inner edge seated on a portion of said base plate, and a spring-biased plate member for biasing said diaphragm against the inner edges of the said base plate and said base plate against said casing.

3. In a bushing for high tension electrical apparatus including a tubular casing of insulating material having a stud extending axially therethrough and projecting beyond an end thereof, said stud having a portion thereof fixed with respect to said casing; a cap extending about the projecting portion of said stud and having an opening larger than the adjacent end face of said casing in the bottom thereof, means for securing said cap to said stud, a base plate proportioned to seat on said adjacent end face of said casing and extend into said bottom opening in movable relationship to said cap to retain the opening substantially closed throughout a predetermined range of movement therebetween, a flexible diaphragm disposed within said cap for sealing the bottom thereof between the opening and said base plate, means for resiliently biasing a portion of said diaphragm against said base plate and said base plate against said casing, and means for limiting the extension of said plate into said cap during the assembly of the bushing.
4. In a bushing for high tension electrical apparatus including a tubular casing of insulating material having a stud extending axially therethrough and projecting beyond an end thereof, said stud having a portion thereof fixed with respect to said casing; a metallic cap extending about the projecting portion of said stud and having in its bottom an opening larger than the adjacent end face of said casing, means for securing said cap to said stud, a base plate proportioned to seat on the adjacent end face of said casing and extend into said bottom opening in movable relationship to said cap, said base plate including a main metallic portion with a perimetral portion of insulating material disposed adjacent to the surface of said cap to insulate it therefrom, a flexible metallic diaphragm sealed to said cap and extending to said plate to seal the space therebetween, insulating means disposed between said diaphragm and said plate to prevent electrical contact therebetween, means for exerting a sealing pressure on the insulated joint between said diaphragm and said plate and on the joint between said plate and said casing, an insulating cover surrounding said stud within said casing and adjacent said base plate to insulate it from said base plate, conducting material surrounding said insulating cover within said casing, electrical conducting means for connecting said plate to said conducting material, and readily disconnectable means for electrically connecting said plate to said cap.

ALEXANDER A. SKVORTZOFF.
